UNITED STATES PATENT OFFICE.

EDWARD E. WHITMORE, OF CHICAGO, ILLINOIS, ASSIGNOR TO THE CURTAIN SUPPLY COMPANY, OF NEWARK, NEW JERSEY, A CORPORATION OF NEW JERSEY.

CAR-DIAPHRAGM.

1,095,760.

Specification of Letters Patent.

Patented May 5, 1914.

Application filed December 22, 1913. Serial No. 808,112.

To all whom it may concern:

Be it known that I, EDWARD E. WHITMORE, a citizen of the United States, residing at Chicago, in the county of Cook and State of Illinois, have invented certain new and useful Improvements in Car-Diaphragms, of which the following is a specification.

My invention has for its principal objects the provision of an effective and economic connection between the meeting edges of the diaphragm plaits whereby the diaphragm construction is stiffened vertically, laterally and longitudinally of the car against any tendency to collapse and the fabric is protected against the destructive effect of the entrance of grit and water between the edges of the plaits.

A further feature of the invention is the provision upon each side of the diaphragm of a vertically opening plait, the members of which are when closed housed within the protective binding strip and which are, whether open or closed, stiffened and guided against deformation.

Other advantages attendant upon distinctive features of the invention will be rendered apparent from the following detailed description based upon the accompanying drawings in both of which are set forth by way of illustration only, a preferred embodiment of the invention.

In the drawings—Figure 1 is a side elevation of the diaphragm in its closed position; Fig. 2 is a similar view showing the open plait; Fig. 3, is a longitudinal section through the top of the diaphragm; Fig. 4 is a fragmentary vertical longitudinal section through the meeting edges of the plait showing the hinged connection. Fig. 5 is an enlarged detail cross sectional view of one of the separable fastenings; and Fig. 6 is a similar view showing one of the permanent fastenings.

Herein the reference numeral 11 designates generally the end plate of a car between which and the face plate 12 of the car vestibule diaphragm is arranged the bellows-like plaits 13, 13 which may be of V-shape or U-shape in cross section, the latter being chosen for purposes of illustration. The edges of the plaits adjacent the end plait 11 and the face plait 12 are connected thereto respectively by angle bars 14 and 15 overlying the edges of the plaits and rigidly fixed to the respective plaits by means of bolts or

screws in the usual manner. The meeting edges 16, 16, of the two plaits are provided with stiffening members 17 and 18 preferably of metal and arranged marginally upon opposite sides of the two edges of the plait. 60 The stiffening member 17 is advantageously and as shown in the form of a flat bar while the member 18 is in the form of an angle bar having a flange 18 which overlies the edges 16, 16 of the plaits and also the outer edge 65 of the companion stiffening bar 17. The stiffening members 17 and 18 extend throughout the height of the diaphragm and also across the top of the same and are preferably formed integral, except as herein- 70 after stated, so as to impart a considerable degree of rigidity against and oppose any tendency to collapse either in a vertical or lateral direction.

The two stiffening members 17 and 18 may 75 be connected together and clamped upon the intervening edges 16 of the plaits throughout their extent by means of permanently applied rivets 20, 20 or the stiffening member 17 may upon each side of the diaphragm 80 be formed in two parts, the lower part being hinged to the upper part at 21 so as to swing forwardly and in a vertical plane in order to permit the face plate to be tilted to give 85 access to the buffering mechanism for repair or replacement. In such case the connection between the stiffening members 17 and 18 below the hinge 21 is effected by readily separable means such for instance as studs 22, 22, passing through apertures of the dia- 90 phragm plaits and provided with cotter pins 23, 23, the apertures in the fabric being protected by means of gromets 24, 24.

It will be observed that not only throughout the one piece portion of the stiffening 95 members, but also including the hinged portion the edges of the plait in both their open and closed position are stiffened laterally, vertically and longitudinally of the car, while in the closed position of the hinged 100 portion the edges of the plaits are protected throughout their extent by being housed within the flange 19 of the stiffening member 18, the hinged portion of the stiffening member 17 swinging into and out of the 105 housing formed by the flanged stiffening member 18 whereby at all times the edges of the plait are stiffened and protected.

Ordinarily, recognizing the necessity of protecting the edges of the plaits from the 110

elements and from entering dust, the meeting edges of the plaits are covered by a binding strip of flexible fabric such as canvas, pantasote, or leather, the application of 5 the same necessitating considerable expenditure of time in stitching by means of expensive machines whereas by the present invention the edges are not only efficiently protected at a great saving in expense, but they 10 are also stiffened and the proper shape of the diaphragm is preserved thus improving the appearance and increasing the life of the vestibule diaphragm construction.

I claim:

- 15 1. In a car diaphragm, a plurality of plaits, a substantially rigid bar disposed marginally of a plait on the opposite sides of the diaphragm, fastening means uniting the bars to the margin of the plaits, the fastening means between the lower portions of the bar and plait being readily releasable in a direction longitudinally of the car whereby to permit the separation and re-attachment of the walls of the plait, substantially as described.
- 20 2. In a car diaphragm, a plurality of plaits, a pair of substantially rigid bars disposed marginally on each side of the plait, and fastening means uniting the bars upon the edges of the plait, one of the bars being in two parts hinged to swing longitudinally of the diaphragm the fastening means uniting the swinging portion of the hinged bar to the companion bar being readily separable, substantially as described.
- 25 3. In a car diaphragm, a plurality of plaits, a substantially rigid L-bar disposed marginally of the plait and fastening means uniting the edges of the plait and the bar, 30 said bar having its flange overlying the edges of the plait at substantially right angles to the walls of the plait, substantially as described.
- 35 4. In a car diaphragm, a plurality of plaits, a pair of substantially rigid bars disposed marginally one on each side of the plait exterior, and fastening means uniting the bars and the edges of the plait, one of 40 said bars having a flange overlying the edges of the plait, substantially as described.
- 45 5. In a car diaphragm, a plurality of plaits, a pair of substantially rigid bars disposed marginally one on each side of the plait, and fastening means uniting the bars upon the edges of the plait, one of 50 said bars having a flange overlying the edges of the plait, substantially as described.

plait, and fastening means uniting the bars upon the edges of the plait, one of said bars 55 having a flange overlying the edges of the plait and the edge of the companion bar, substantially as described.

6. In a car diaphragm, a plurality of plaits, a pair of substantially rigid bars disposed marginally one on each side of the plait, and fastening means uniting the bars upon the edges of the plait, one of said bars having a flange overlying the edges of the plait, one of the bars being in two parts 60 hinged to swing longitudinally of the diaphragm, the fastening means uniting the swinging portion of the hinged bar to its companion bar being readily separable, substantially as described.

7. In a car diaphragm, a plurality of plaits, a pair of substantially rigid bars disposed marginally one on each side of the plait, and fastening means uniting the bars upon the edges of the plait, one of said bars 75 having a flange overlying the edges of the plait and the edge of the companion bar, one of the bars being in two parts hinged to swing longitudinally of the diaphragm, the fastening means uniting the swinging portion of the hinged bar to its companion bar being readily separable, substantially as described.

8. In a car diaphragm, a plurality of plaits, a substantially rigid L-bar disposed 85 marginally of the plaits and extending continuously across the top and down each leg thereof, and fastening means uniting the bar upon the margins of the plaits with its flange overlying the edges thereof, substantially as described.

9. In a car diaphragm, a plurality of plaits, a pair of substantially rigid bars disposed marginally of the plaits one on each exterior side thereof and extending continuously across the top and down each leg thereof, and fastening means uniting the bars and the edges of the plaits, substantially as described.

In testimony whereof I have hereunto 100 signed my name in the presence of two subscribing witnesses.

EDWARD E. WHITMORE.
